[57] CLAIM

The ornamental design for a coal burning stove, as shown and described.

DESCRIPTION

FIG. 1 is a front elevational view of a coal burning stove showing my new design;

FIG. 2 is a rear elevational view thereof;

FIG. 3 is a top plan view thereof;

FIG. 4 is a bottom plan view thereof;

FIG. 5 is a side elevational view thereof;

FIG. 6 is an elevational view of the opposite side thereof; and

FIG. 7 is a front elevational view of a second embodiment of a coal burning stove showing my new design, the side elevational views thereof as well as the top and bottom plan views thereof and the rear view thereof being identical to those of the first embodiment.
